UNITED STATES PATENT OFFICE.

ALLEN H. KELLS, OF ADRIAN, MICHIGAN, ASSIGNOR OF ONE-HALF TO FREDERICK C. SCHOLL, OF ADRIAN, MICHIGAN.

MOLDING-MACHINE.

1,178,728.

Specification of Letters Patent. Patented Apr. 11, 1916.

Application filed September 12, 1914, Serial No. 861,464. Renewed February 24, 1916. Serial No. 80,307.

To all whom it may concern:

Be it known that I, ALLEN H. KELLS, a citizen of the United States, and a resident of Adrian, in the county of Lenawee and State of Michigan, have invented a certain new and useful Molding-Machine; and I do hereby declare the following to be a full, clear, and exact description of the invention, such as will enable others skilled in the art 5 to which it appertains to make and use the same, reference being had to the accompanying drawings, and to the characters of reference marked thereon, which form a part of this specification.

15 My invention relates to molding machines. It particularly relates to cement and sand or concrete tile-making machines.

It has for its object to produce an efficient easily constructed, rapidly operating tile 20 molding machine.

By my invention the tile may be mechanically tamped and drawn. The parts are manually controlled and may be mechanically or manually actuated. Modifications 25 may be made so that the parts may be automatically inter-controlled.

The invention may be contained in many forms of constructions usable for different purposes, all of which come within the pur- 30 view of my claims hereinafter appended. To show the practicability of my invention, I have selected one of such constructions as an example and shall describe it hereinafter. The construction selected is illustrated in 35 the accompanying drawings.

Figure 1 of the drawings illustrates a side view of a construction containing my invention. Figs. 2, 3 and 4 illustrate details of the tamping mechanism. Fig. 5 is a top 40 sectional view on the line 5—5 indicated in Fig. 1. Fig. 6 is a vertical sectional view through the mold and pattern or core. Fig. 7 is an annular plate for removing the molded tile from the machine. Fig. 8 is a 45 side view and Fig. 9 is an end view of the tamper. Figs. 10 and 11 are sectional views of a modification of the construction illustrated in Fig. 1 taken along the lines indicated in the figures. Fig. 12 illustrates a 50 draft block and Fig. 13 illustrates a draft pin for drawing the core of the molding machine.

1, Fig. 1 are supporting legs to which is secured a table top 2. The table top 2 is 55 supported on shoulders and is locked in po-

sition by means of rings 3 which are keyed or bolted to rods 4 which form extensions of the legs, 1. A shelf 5 is also supported on the legs 1 and between the rings 6 which are secured to opposite sides of the shelf 60 5 to the rods 4. The position of the shelf 5 may be adjustably located by shifting the position of the rings 6 along the rods 4. The parts may be supported on the base 7.

A driving pulley 10 may be connected by 65 means of a belt with a suitable source of power and driven thereby. The pulley 10 is keyed to the shaft 11 which is supported in suitable bearings in two of the legs 1. A set of reverse friction cones 12 is connected 70 to the shaft 11 and is shiftably keyed by means of a feather key 13 to the shaft 11. The reverse double headed friction cone 12 may be shifted to reverse the operation of the mechanism by any suitable means such 75 as the bell crank lever 14 which is connected to the reverse double cone 12 through a slip ring 15. A shaft 16 is supported in bearings located in the table top 2 and in a bracket 17. The bracket 17 is secured to two 80 of the legs 1. A pinion 18 is keyed to the shaft 16. A gear wheel 19 is supported above the table top 2 and is keyed to a shaft located in the table top. The upper end of the shaft is secured by a washer and nut 85 20. The pinion 18 meshes with the gear wheel 19 and causes rotation in one direction or the other according to the position of the double reverse friction cone 12.

Flasks 25 are hingedly connected to the 90 top of the gear wheel 19. The flasks 25 are located on opposite sides of the center of the gear wheel 19 and over openings 26 in the gear wheel having a size substantially 95 the same as that of the inner diameter of the flasks. The flasks 25 may be positioned on annular sheet metal bases 27 which form flanges 28 which extend inwardly a short distance over the openings 26. An annular sheet metal plate 29 may be located between 100 the hinges 30 which connect the parts of each flask 25 to the gear wheel 19. It is located concentric with the flask 25 and the opening 26 and covers the inwardly extending flange 28. The parts of the flasks may 105 be locked together by any suitable means such as by pins or bolts 31. When the molded material is being removed the flask 25 is unlocked and the parts are separated by being opened on the hinges 30. Whereupon 110

the molded tile may be removed by lifting on the plate 29. For convenience of handling the plates 29, they are provided with extending ears 32. The ears 32 may be easily seized and the molded tile lifted from the gear wheel 19 and removed from the machine.

A core 40 is supported in a cylinder 41 formed in the table top 2. The core 40 is movable vertically in the cylinder 41 and may be raised upwardly and into the center of each flask 25 when the flask 25 is placed over the cylinder 41. The core 40 may be raised and lowered by means of a pinion 42 and a rack 43. The rack 43 is connected to the core 40 and moves in a bracket 44 which is connected to the lower end of the cylinder 41. The rack 43 is provided with a key 45 which prevents rotation of the rack 43 while it is being operated upon by the pinion 42. The pinion 42 may be connected to the same source of power to which the wheel 10 is connected, or it may be manually operated by the crank 46 which is connected to the shaft 47 to which the pinion 42 is keyed.

The core 40 is provided with a flange 48 which is substantially the same diameter as the inner diameter of the cylinder 41 and 30 co-acts with the rack and its bearing to guide the core 40 as it is moved vertically in the cylinder 41. When the core 40 is lifted into position in the flask 25 the flange 48 makes contacts with the inwardly extending flange 28 and operates to prevent the escape of any material from the bottom of the flask 25.

The core 40 is divided into two parts 49 and 50. The plane of division extends 40 through the axis of the core and at a slight angle thereto. The part of the core having a larger portion of the bottom of the core is first drawn and then the other is drawn. The withdrawal of one of the wedge-shaped 45 parts of the core along the inclined plane of division reduces one diameter of the core and gives room for easy withdrawal of the core from the molded material. The rack 45 is provided with a rod 51 which extends 50 up through the center of the core and through the top 52. The top 52 is secured by means of threaded screws 53 to the part 49. The rod 51 is provided with a ring 54 which is keyed to or forced on to the rod 51. The parts 49 and 50 are provided with 55 inwardly extending bifurcated fingers 55 which are located on opposite sides of the block 56 which is also secured to the rod 51. The part 50 of the core 40 is provided with 60 pins 57 which extend up from the bottom of the part 50 of the core into a shoulder formed in the part 49 of the core and operate to guide the resetting of the parts relative to each other. When the rack 43 is 65 drawn downwardly the pin 51 pulls the ring

or shoulder 54 against the inwardly extending finger 55 and the part 50 is drawn down with the rack until the block 56 reaches the other finger 55 whereupon both parts of the core will be drawn downwardly. As the 70 part 50 is shifted relative to the part 49 the two parts slip along the inclined division plane reducing thereby one of the diameters of the core. This permits easy withdrawal of the core without mutilation of the molded 75 form contained in the flask 25.

The molded material may be evened or cut off in the plane of the top of the flask by means of the horizontal plate 60 which moves laterally across the top of the flask 80 in a channel 61 located in the shelf 5. The plate 60 may be actuated by any suitable means such as the bell crank lever 62 which is pivoted on one of the rods 40. When the flask has been filled with material about the 85 core 40 the upper end of the molded material is evened off by swinging the arm 62 so as to push the plate 60 over the top of the flask and thus shear or cut off the molded material.

The shelf 5 is provided with the hopper 65 which registers with an opening 66 formed in the shelf 5. The opening 66 is located in the axial line of the cylinder 41 so that when the flask 25 located on the 95 gear wheel 19 is made to register with the cylinder 41 the top of the flask 25 will also register with the opening 66 located in the shelf 5 and with the bottom of the hopper 65. Material such as a mixture of cement 100 and sand or any other suitable moldable or plastic or settable material may be shoveled or inserted into the hopper 65 and the hopper 65 will feed the material into the flask 25 and around the pattern or core 40 when 105 the core is in position in the flask 25. The material may be tamped as the flask is filled by means of the tamper 70.

The tamper 70 is provided with two spatulate parts 71 connected through a hub or 110 head 72 to a vertical rod 73. The spatulate parts are provided with lower wedge-shaped ends 74 and have inclined leading surfaces 75 which near the ends 74 form a sharp wedge-shaped edge 76 which terminates rearwardly 115 into a tamping horizontal or flat surface 77 located between the beveled edges or sides 78. As the tamper 70 is rotated and raised and lowered vertically the leading inclined surface 75 operates to collect and direct the 120 material downwardly while the sharp corner 76, together with the beveled edges 78 operates to spread the material laterally and the material is then brought under the operation of the flat tamping surface 77 125 which tamps the material into position between the core and the wall of the flask as the tamper is actuated both vertically and rotatively. The rod 73 is provided with a feather 79 and is rotatively connected with 130

the gear wheel 80. The gear wheel 80 is supported in a bearing located in the bracket 81 which is connected to the frame 82. The gear wheel 80 is rotated by means of bevel gear wheel 83 which is connected to the shaft 84 which is located in bearings formed in a bracket 105 which is also secured to the frame 82. A suitable driving mechanism may be connected to the shaft 84. In the present instance a sprocket wheel 85 is keyed to the shaft 84 and is driven by the sprocket chain 86 through which it is connected to the sprocket wheel 87 loosely mounted on the driving shaft 11. A ring 88 is feather keyed to the shaft 11 and is shifted by means of the bell crank lever 89 supported on a bracket 93. The sprocket 87 and the rim 88 may be provided with clutch engaging fingers or faces 90 whereby the operation of the bell crank lever 89 will connect the driving shaft 11 with the bevel gear wheels 80 and 83 through the sprocket wheels and chain.

The rod 73 is guided in its vertical movements by means of a right angular portion 25 of the upper end of the frame 82 which embraces a ring 91. A ring 92 is adjustably secured to the rod 73 intermediate along its length. It is provided with two beveled pins 93 extending at right angles to the axis of 30 the block 92 and the rod 73. A rack 94 having inclined wedge-shaped teeth 95 is supported on a bracket 96 which is secured to the supporting frame 82. As the rod 73 is rotated by the operation of the gear wheels 35 80 and 83 the beveled fingers 93 enter between two consecutive teeth of the rack 95 and by reason of the inclined relation of the teeth of the rack 95 the rod is lifted and allowed to drop. As the tamper 70 changes 40 in its vertical position on account of the filling of the flask 25 the ring 92 is raised along the rack 94 and consequently the teeth 95 of the rack 94 are engaged one after the other until the tamper is forced from the 45 flask 25. The position of the rod 73 and consequently of the tamper 70 relative to the flask 25 and of the ring 92 relative to the rack 94 may be controlled by the lever 98 which is pivoted to the upper end of the 50 bracket 96 and is connected at one end by means of the link 99 to the ring 100 which is positioned on the rod 73 so as to engage the ring 101 which is locked to the rod 73. The lever 98 may be operated by the rod 102 55 which is connected to one end of the lever when it is desired to lift the rod 73 and remove the tamper 70 from the flask 25.

In the operation of the machine the core 50 is inserted in the flask 25 and the material 60 is tamped in around the core until the flask is filled, whereupon the tamper is withdrawn by the operation of the lever 98 and the upper end of the molded material is evened off by the operation of the lever 62. The core 50 is then withdrawn by the rota-

tion of the pinion 42 which draws the core 50 from the flask 25. The reverse friction clutch mechanism 12 is then operated by the lever arm 14 so as to produce rotation of the gear wheels 18 and 19 which carries the flask 70 24 containing the molded material from beneath the shelf 5 and brings the other flask into register with the cylinder 41 containing the core 40 and with the hopper 65 on the shelf 5. As the other flask is being 75 filled and tamped after the core has been lifted into position, the molded material formed in the first flask may be removed by lifting the plate 29. In this way the tiles may be formed and removed one after the 80 other.

The modifications shown in Figs. 10 and 11 are provided with as many cores as there are flasks and the cores may be drawn and returned to the flask by the rotation of the 85 gear wheel 19. The cores 110 and 111 are carried in the gear wheel 112 which is keyed to the shaft 113 supported in the stepped bearing 114 located in the base 115 which is connected to the legs 1. The shaft 113 is 90 also supported in a bearing contained in the shelf 5. The cores 110 and 111 are connected to rods 116 having channels 117. The rods 116 are vertically movable in the ends of a cross arm 118 having bolts 119 which 95 extend into the channels 117 and prevent the rotation of the rods 116 with respect to the cross arm 118. The cross-arm 118 is locked to the shaft 113 by means of a machine bolt 120. The rod 118 moves with the gear wheel 112. The gear wheel 112 and the cross-rod 118 carry the cores 110 and 111 in a vertical position. They are guided by the openings 121 formed in their vertical movements in and out of the flasks 25. The 100 lower side of the gear wheel 112 is provided with recesses formed around the edges of the openings 121 into which the flanges 122 located on the flasks 110 and 111 may be inserted when the cores are placed in the flasks 105 25 so as to prevent the escape of the material by the lower ends of the cores 110 and 111.

A block 125 is adjustably secured to each rod 116 by a lock pin 126. The block 125 is provided with a pin 127 having an oblong head 129. The head 129 is provided with rounded wedge-shaped ends 130. The head 129 moves in a channel 131 which is formed between two strips 132 located elliptically one above the other on a depending cylinder 133 connected to the table top 134. The channel 131 is located in the plane extending at an angle to the axis of the shaft 113 so that as the shaft 113 is rotated and the pin heads 129 are carried around by arm 118 and the gear wheel 112, the heads will be raised and lowered by the channel 131 which will draw and raise the rods 116 and the cores 110 and 111 vertically.

In the operation of the form of the in- 130

vention illustrated in Figs. 10 and 11, the material may be tamped and molded on one side of the machine and as the flask is carried around by the gear wheel 112 the 5 core will be withdrawn from one flask 8 at the same time it will be inserted into the other flask so that when the other flask arrives in position beneath the hopper 65 the core of the other flask will be in position 10 within the flask. The molded material contained in the first flask may then be removed by opening the flask as before and lifting the molded material from the machine.

The construction selected and described, 15 may be greatly varied in the arrangement and manufacture of its parts and in the substitution of elements having equivalent functions and such modifications may be used for many varied purposes and still contain 20 the invention.

Having thus described my invention, what I claim as new, and desire to secure by Letters Patent, is,—

1. In a molding machine, the combination 25 of a core composed of two parts divided in a plane at an angle to the axis of the core, a rod extending axially through the core, the rod having a pair of shoulders, an ear extending inwardly from one of the 30 parts of the core, and between the shoulders of the rod, the other of said parts also having an ear extending inwardly and located in spaced relation with respect to one of the shoulders, means for drawing the rod to 35 successively start the parts of the core and then move the parts of the core together.

2. In a molding machine, the combination 40 of a core composed of two parts divided in a plane at an angle to the axis of the core, a rod extending axially through the core, the rod connected to one of the parts of the core, the rod and the other part of

Copies of this patent may be obtained for five cents each, by addressing the "Commissioner of Patents, Washington, D. C."

the core having coacting shoulders located in spaced relation to each other so that the shoulder of the rod will not draw axially 45 one part of the core until after the other part of the core has been drawn axially a short distance and will then draw the parts axially together.

3. In a molding machine, the combination 50 of a core composed of two parts divided in a plane at an angle to the axis of the core, a cap for covering the upper ends of the said parts, a rod axially movable in the said cap and in one of the parts of the core, the rod 55 secured to the other of the parts of the core, engaging members, one located on the rod and the other located on the part other than the one to which the rod is secured and located in spaced relation with respect to each 60 other, means for drawing the said rod whereby the parts will be successively started and will then be moved together.

4. In a molding machine, the combination 65 of a plurality of cores, the cores composed of two parts separated by a plane at an angle to the axis of the cores, a rod for moving the parts of the core axially and having means for limiting the movements of the said parts axially relative to each other and starting 70 them in succession, an elliptical track and means connected to the said rod and moved by said track for drawing the said cores and means for rotating the said cores about an axis exterior to the cores so as to be operated 75 by the said track.

In testimony whereof, I have hereunto signed my name to this specification in the presence of two subscribing witnesses.

ALLEN H. KELLS.
